CLAIM

The ornamental design for a drink cooler, as shown and described.

DESCRIPTION

FIG. 1 is a top, perspective view of a drink cooler showing our new ornamental design;

FIG. 2 is another perspective view thereof, from the front;

FIG. 3 is a top view thereof;

FIG. 4 is a bottom view thereof;

FIG. 5 is a front view thereof;

FIG. 6 is a rear view thereof;

FIG. 7 is a right side view thereof;

FIG. 8 is a left side view thereof;

FIG. 9 is a perspective view thereof, from the bottom;

FIG. 10 is an exploded perspective view thereof, from the top, front; and,

FIG. 11 is another exploded perspective view thereof, from the bottom, front.

The broken lines show portions of the drink cooler and form no part of the claimed design.

1 Claim, 11 Drawing Sheets
